UNITED STATES PATENT OFFICE.

THEODORE DOUGLAS, OF SCARBORO, NEW YORK, ASSIGNOR TO DUPLEX ENGINE GOVERNOR COMPANY, INC., OF BROOKLYN, NEW YORK, A CORPORATION OF NEW YORK.

MECHANISM FOR SAFELY CONTROLLING INTERNAL-COMBUSTION ENGINES UPON AIRCRAFT.

Application filed December 27, 1917, Serial No. 209,130. Renewed April 7, 1927.

My invention relates to an improvement in mechanism for safely controlling prime movers; especially prime movers which are commonly used under conditions which give rise 5 to great liability of accident, and which make imperative the immediate stopping of the operation of the prime mover upon the occurrence of anything that is likely to produce sudden loss of life or property.

10 My invention comprises an attachment that is particularly adapted for internal combustion engines upon aeroplanes and other aircraft; and has for its primary object to provide an attachment which can be combined with the power system of which the engine is the principal part, in such a way that, in case of a mishap of any kind resulting in a great shock to the engine, the operation of the latter is interrupted at once; this 15 cessation of the running of the engine being preferably brought about by the automatic suspending of the operation of the ignition system by which electrical current is supplied to the cylinders of the engine to produce combustion of the explosive charges therein.

A further object of my invention is to provide an attachment which will be simple in construction and capable of being easily applied and connected in operative relation to an aeroplane engine for example, so that it will instantly and infallibly cause the engine to stop, whenever an accident of any sort takes place which is apt to produce serious 30 consequences before the aviator can take measures by hand to insure his own safety and the safety of his machine.

It very often happens when an aviator is making a flight that a propeller blade breaks or something else happens; with the result that the engine immediately becomes so unbalanced as to wrench itself loose from its anchorage before it can be stopped. Frequently in such cases the gasoline line is broken and fire has been known to start as a consequence of the continued sparking in the engine cylinders and the flaming exhaust into the atmosphere before the aviator has time to manipulate the main switch of the ignition circuit; even when such switch is easily within his reach. Under such circumstances the engine may not only tear itself from its fastenings, but even go overboard before the aviator can fully realize what has

come to pass; and when the fire due to the escape of gasoline commences, it invariably, because of the high speed of the aeroplane, trails backward. The flames can thus envelop the aviator entirely and the end of both flier and flying machine may then be but a matter of a few seconds.

Such breakages are infrequent under ordinary conditions, but likely to happen, from gunfire and accidentally, in war. When an aviator is in action he needs both hands and feet for his weapons and controls. Should a blade break or be shot off, he has small chance of saving; for even if he recovers management, he necessarily sacrifices altitude; which is priceless and determines whether he can pass the enemy's barrage and get back into his own territory.

My invention aims to eliminate the danger of accidents such as I have just outlined by mechanism which is quite simple, involving relatively few parts and comprising no construction which is bulky, complicated or expensive; and which can be mounted upon an aeroplane or other airship so that it will instantly respond to an abnormal vibration or other bodily movement of the engine driving the same, in order to cut off the flow of ignition current to the spark plugs and cause the engine to stop developing power. In this way, in case a propeller blade should break, or something else should happen to unbalance the engine, the danger of the latter tearing itself loose and causing a destructive fire is fully obviated.

Other objects and advantages of my invention will more clearly appear from the following description, taken in connection with the accompanying drawings forming a part of the same; and the characteristics of my invention will be precisely defined in the appended claim. This disclosure, however, is explanatory only, and I reserve the right to adopt embodiments of my invention other than what is actually shown herein to the full extent indicated by the general meanings of the terms in which the claim is expressed.

On the drawings:—

Figure 1 is a diagrammatic view showing a complete power system for an airship, such as an aeroplane, for example; and the manner in which mechanism according to my invention is utilized thereon;

Figure 2 is a diagrammatic view of an aeroplane with engine and propeller thereon, showing mechanism according to my invention carried near the engine in front of the aviator, the observer viewing the parts mentioned from a point back of the engine;

Figure 3 is a diagrammatic view of an aeroplane engine with its propeller, showing further the manner in which my invention is mounted in relation to the engine;

Figure 4 is a plan view of a casing for enclosing mechanism used in the practice of my invention;

Figure 5 is a plan view of the same casing showing the parts enclosed thereby, the cover being taken off;

Figure 6 is an inside view of the cover of the casing, showing the manner in which certain electrical connections are made to the inside of the casing;

Figure 7 is a section on the line 7—7 of Figure 4;

Figure 8 is a section on the line 8—8 of Figure 4;

Figure 9 is a central longitudinal section taken vertically through Figure 4; and

Figures 10 and 11 are diagrammatic views showing how my attachment can be modified.

The same numerals identify the same parts throughout.

Referring to the first figure on the drawings, I show at 1 an internal combustion engine supplied with ignition current through high-tension conductors 2, leading to the spark plugs of the engine from a magneto 3. This magneto may be of any approved design, with primary and secondary windings; and it is connected by a conductor 4 to a switch 5 which is joined by a conductor 6 to ground at 7. The switch 5 may be of the two-pole single-throw type, and is illustrated in open position; but when it is closed, the primary armature winding will be short-circuited around the circuit breaker or timer of the magneto in the usual way by the ground connection provided through the conductors 4 and 6 and the operation of the ignition system will be suspended; so that the engine cannot continue running. My safety attachment for the engine is indicated as a whole at 8; and it is in multiple with the switch 5 through a conductor 9 connecting it to the conductor 4, and another conductor 10 joining it to the conductor 6. The arrangement of the parts of the attachment 8 is such that, as I shall set forth fully hereinafter, the attachment 8 will automatically cut off the ignition current by short-circuiting the magneto to the ground 7; and it is adapted to be operated by any abnormal bodily movement of the engine, as when there is an unbalanced condition resulting from a broken propeller blade. In that event the torque of the engine, which would

be normally divided by the blades and thus produce a balanced load, is then no longer properly divided; producing a badly unbalanced load, and pushing the engine from side to side as the propeller revolves. Under such circumstances, a tractor plane is liable to go into a dive; a pusher plane into a tail-stall; and, either is apt to pass next into a tail-spin, and the engine may or may not go overboard entirely, this side pressure does

become so great that engine is broken from its foundations and thrown out of the airship, the center of gravity of the machine is upset, completely destroying its equilibrium, and effecting other and more serious damage.

The attachment 8 produces a suspension of the operation of the ignition system to stop the engine chiefly through the instrumentality of an element such as a pivotally mounted bar 11, comprised in the attachment 8, and housed in a casing 12. See Figure 5. This bar has sufficient mass, and it is supported upon its pivot 13 in the casing 12, so that it can move or swing or oscillate, like a pendulum, in a direction that extends across or transversely of the longitudinal axis of the engine 1; that is, the axis of the crankshaft of same. Hence the bar should preferably swing parallel to the plane of the propeller. The method of mounting referred to is illustrated in Figures 2 and 3. I may secure the attachment 8 to any part of the aeroplane so related to the engine that any transverse jar will instantly be transmitted to the bar 11; hence I can mount the attachment either upon some part of the engine framework directly, or upon a part of the aeroplane rigid with it or near enough to it to be subject to its vibration, such as the dashboard or instrument board

14. In front of the engine, on the shaft 15, will be the propeller 16, and at 17 is the outline of a part of the lifting planes or wings of the aeroplane. I secure to the back of the casing 12, a T-shaped fastening element having openings at the ends of the stem and arms, to enable the casing to be maintained in the required position. As indicated in Figures 2 and 3, the casing 12 and bar 11 are both in vertical position, and the bar, to stop the engine, swings in a direction transverse to the crankshaft 15. I may also mount the casing 12 so that it will be horizontal and the bar 11 will normally lie parallel to the crankshaft. However, the bar 11 will still be in position to swing in a direction transverse to the crankshaft, and the attachment can therefore perform its function when needed quite as easily as in the first instance, to respond to a transverse shock to the engine 1.

The casing 12 and parts borne thereby are illustrated in Figures 4 to 9 inclusive. It comprises a casting 19, forming the sides and ends; the upper end of the casting contract-

ing somewhat, so as to give it approximately the shape of a bell. This casting 19 may be of metal but the bottom 20 and cover 21 of the casing are of some insulating substance, such as fiber or rubber. To the bottom 20, near the upper end of the casing is fixed an inverted metal yoke 22 in which is carried the pivot pin 13 whereon the bar 11 is hung; and near the opposite end of the 10 casing there are fixed to the bottom 20 two contact elements 23; one on each side of the bar 11. As will appear presently, whenever the bar 11 is constrained by the motion of the engine 1 to swing sidewise into engagement 15 with either element 23, the conductors 9 and 10 will be connected together, grounding the magneto, and stopping the engine 1 promptly. For the purpose of enabling the bar 11 to engage the contact elements 23 properly I 20 secure to each side of the bar 11 a spring contact element or brush 24, which will be pressed against the adjacent element 23 over virtually its whole length when the bar 11 is jolted or shaken to a sufficient extent to 25 make it perform its function.

On the outside of cover 21 of the casing 12 are located two electrical terminals or binding posts 25; one joined to the conductor 9 and the other to the conductor 10. The 30 binding post 25 at the left in Figure 4 is secured to the overlapping ends of a pair of diverging strips 26 of electrically conductive material on the inner face of the cover 21; and the opposite end of each of these strips 35 is made fast to a leaf spring contact element or brush 27. The shank or stem of the post 25 mentioned may have a nut on its inner or lower end to be screwed up tight against the two strips 26, as shown in Figure 6; and the 40 elements 27 may be fastened in place by screws extending from the outer face to the inner face of the cover 21, and through the strips 26; nuts being applied to the inner ends of these screws and turned up against 45 spring brushes 27 and strips 26. See Figure 6. From the stem of the other binding post extends a single conductive strip 26, on the inner face of the cover 21, to a central contact element 28, on the outer face of the cover 1, and, 50 as is illustrated in the two views last referred to, the contact 28 may have a threaded shank passing through the cover, and the inner end of this shank may receive a nut to fasten the shank and the single strip 26 together. The 55 single strip 26 may be joined to the other binding post in the same way as the first binding post is joined to the two overlapping strips 26.

To cooperate with the contact 28 I utilize 60 a switch 29, on the outer face of the cover 21; and mounted on a metallic pivot or journal carrying on the inner face of the cover 21 a leaf-spring contact brush or element 27; similar to the elements 27 already 65 mentioned. The switch 29 may be attached

to this pivot in any convenient manner and the end of this pivot on the inner face of the cover may carry a nut to hold the element 27.

When the cover is applied to the casing, to which it is secured by screws or the like, 70 the leaf springs 27 at the ends of the diverging strips 26 connected to the post at the left in Figure 4 will each rest on one of the contact elements 23; and the spring brush 27 under the pivot of the switch 29 will rest on 75 the pivot 13. With the switch 29 engaging contact 28, obviously whenever the bar 11 is swung so as to move either brush 24 against the adjacent contact element 23, current will flow from the magneto 3 through 80 conductor 9, one of the diverging strips 26, through the bar 11, switch 29, contact 28, and the binding post at the right to the conductor 10 and the framework of the engine 85; and the further operation of the engine will thus be prevented.

The elements 23, strips 26, brushes 27, switch 29, and contact 28 therefore constitute conducting means or connections in the 90 casing attached to the posts 25; and these posts or terminals are connected or bridged by means consisting chiefly of the bar 11, under predetermined conditions, to ensure the object sought after. Whenever a ground connection is thus established, upon the occurrence of a serious accident that might otherwise destroy the flying machine and kill the flier, the engine is stopped instantly; fire is made impossible, and the aviator can 95 volplane easily down to terra firma without having to run the risk of further damage of any sort.

To enable the aviator to make sure that the bar 11 is in central or neutral position under ordinary circumstances, I make a 105 transverse slot 30 in the cover 21, and to the bar 11 I fix an index element or pointer 31 which projects through the slot. The middle of this slot is marked by two lines 32, one at each edge. When the pointer 31 is 110 between these lines, the bar 11 is away from both contact elements 23. When it is at either end of the slot, the aviator knows that the bar is in engagement with one of 115 these elements 23.

After the bar 11 is jolted into engagement with one of the elements 23, in consequence of a mishap to the aeroplane, it is held against return to neutral position by suitable retaining means. Therefore, when the 120 engine is once stopped, it cannot resume operation until the bar 11 is released by hand. To this end I form each element 23 with a pair of lugs 33, arranged side by side, and by each pair of lugs is supported a catch 34. The lugs of each element 23 carry a pivot pin 35, and this pivot pin passes through the catch located between said lugs. On the top of the lugs 33, moreover, the leaf 125 spring 27 connected to the diverging strips 130

- 26, connected to the binding post 25 at the left, will rest. Both catches 34 are preferably of insulation, but each will have a metal inset 36, which is formed to provide a shoulder or hook on the lower side of its catch; presenting this shoulder or hook towards the lugs 33 supporting the catch. See Figures 7 and 8. On the upper face of the bar 11 is a lug or projection 37, and when the bar oscillates too much, this projection will slip under one of the catches till the shoulder or hook of the insert 36 therein engages it. The lower ends of the inserts 36 in front of the shoulders are bevelled; and so are the ends of the under faces of the catches, as Figures 7 and 8 indicate; so that when the bar 11 swings far enough, the projection 37 can slip easily under one or the other catch; this catch being free to lift slightly till the shoulder on its inset 36 snaps over the projection 37 and holds the bar against backward movement. Hence the short-circuiting of the magneto 3 is made permanent and certain.
- 28 To release the catches, the end of each between the pivot pin 33 thereof and the inside of the casing is engaged by appropriate means such as a plunger 38 in the cover 21. Each plunger has a stem extending through the cover and carrying adjacent the outer face of the same a head 39. Between this head and the cover is a spring 40. By pressing the heads 39, either catch can be operated to raise its end having the inset 36 to free the bar, and allow it to move back. Normally the ends of the catches under the plungers 38 are also engaged by compression springs 41 which act to cause the bevelled lower faces of the opposite ends of the catches to rest lightly on the bar 11.
- Between the pivot 13 and the leaf-spring elements 24, the bar 11 is engaged by compression springs 42 one at each side. Each of these springs bears in a pocket 43 of a lug 44 on the bottom 20. The free end of the bar also carries a pin 45 which projects through a slot in the adjacent part of the casting 19; and to this pin are secured two other springs 46, one at each side. Each pair of springs 42 and 46 constitutes means for damping the oscillations of the bar, and prevent it from engaging one of the contacts 23 under ordinary conditions. Each pair of springs also serves to restore the bar 11 to neutral position after one of the catches snaps over the projection 37, and is moved to release the bar 11. I also join the opposite ends of the springs 46 to eyelet bolts 47, each of which has a head 48, movable in the bore of a boss 49. The bosses 49 are at opposite sides of the casting 19, and the threaded outer ends of the bolts 47 carry nuts 50 and lock nuts 51. By manipulating the nuts 50 the bar 11 can be moved to exact central position, with the pointer 31 be-

tween the lines 32; and it will so remain when the lock nuts 51 are made tight, until occasion requires it to swing away from central position. The springs 46, with the bolts 47 and nuts thereon thus serve also as means for adjusting the bar 11 in addition to damping it, and by means of the bolts 47 and nuts 50, the tension of the springs 46 can be regulated as desired.

On the outer face of the cover 21 is a centrally located mark or indication just below the contact 28. When the switch 29, which controls the connections to be bridged by the bar 11, is in engagement with the contact 28, the indication 52 will be hidden and the operator will know that the attachment 8 is ready to act in case of emergency; but should this mark be visible, the operator will know that he must first close the switch 29 before he can rely on the attachment to do its work. The indication 52 may be made by luminous paint, if desired, so as to be easily visible in the dark.

By means of the pin 45, the bar 11 can be manually moved into position to short-circuit the magneto 3 for testing the instrument; and the switch 5 can be omitted entirely in the practice of my invention.

My attachment is of course not limited to gas engines, or aeroplanes, but may be used with other prime movers, and in other relations as well; if provided with electric circuits essential to regular operation.

My invention can also be applied to pusher planes as well as tractor planes; and on dirigible balloons, because when a propeller on a balloon breaks fragments may puncture the gas bag and liberate the inflammable contents.

My invention is especially useful on military aeroplanes to promote the safety of the aviator against mishaps of the kind that are particularly met with in aerial warfare. In case of damage to a flying machine in a battle between two aviators in the clouds, such damage, if serious enough to threaten the destruction of the aeroplane, would very likely be accompanied by serious injury to the flier. Under such circumstances the aviator could not help himself, even if it were possible to manipulate the switch 5 in order to shut off the ignition current and stop the engine.

Under any circumstances, when an accident happens that causes the unbalancing of the engine, the time interval will generally be too short to enable the switch 5 to be closed; and even if the aviator could close the switch 5, if he has not been disabled, he would generally have enough to do in other directions, and furthermore, he might not have the presence of mind enough to close the switch and save himself, especially if the accident were the first in his flying experience. With the attachment 8

present, the ignition is automatically terminated and sparking ceases so that fire cannot result no matter how much gasline is spilled.

5 The force of the springs on each side of the bar 11 is of course adjusted to make the attachment 8 inoperative within the limits of the safe operation of the engine; causing the pendulum bar to remain neutral 10 until that limit is exceeded.

My attachment is equally well adapted for engines having ignition systems in which current is generated by means of a battery instead of a magneto; and, regardless of 15 the fact whether a battery or a magneto is employed, I may connect it not only in parallel with the electrical generating device as shown in Figure 1; but also in series, if desired. If the attachment is joined in this 20 relation to the primary winding on the armature of a magneto, or to the primary of a coil connected at one end to a battery and at the other end to ground, the pendulum bar 11 must be arranged so that a shock will 25 cause it to break the main circuit of the ignition generator, instead of merely connecting it by a short circuit to ground. I can arrange the parts of my instrument without material alteration, in order to get this result, simply by dispensing with the spring 30 brushes 24 and with the two spring brushes 27 and their strips 26 connected to the binding post 25, shown at the left in Figures 1 and 4. In place of these two strips 35 26 and these two brushes 27, I may employ a single strip 26, and a single brush 27 located near the middle of the wide end of the cover 21, in longitudinal alignment with the pivot post of the switch 29; and this 40 single brush 27 will likewise be connected to the post 25 at the left; and will be arranged to rest directly upon the bar 11, say at a point near the catches 34. So long as the bar is in mid-position the current can 45 flow from the generating device through the main circuit by way of this bar; but whenever the engine sustains a severe shock the bar will swing to the right or left, as before, and be engaged by one of the catches 34, thus 50 breaking contact between the bar and the brush connected to the left-hand binding post and opening the circuit.

It sometimes happens too that when an aviator is making a flight an accident may 55 happen in some other manner than by the breaking of a propeller blade, and may cause a shock to the engine that is more or less parallel to the axis of the crankshaft instead of transverse to the same. Such a situation 60 may result from a collision. If it is desired to guard against such a thing, the attachment 8 can be mounted so that the casing 12 will have its top 21 and bottom 20 parallel with the crankshaft of the engine, and with 65 the bar extending either vertically or hori-

zontally across the crankshaft of the same. With this arrangement a collision producing a substantially longitudinal shock will cause the bar to swing in a plane that is more or less parallel with the engine crankshaft, and 70 suspend the operation of the ignition circuit with the same result as in the first instance. In order to provide against mishaps from longitudinal shocks the attachment may be mounted so as either to short circuit the 75 generator or directly break the main circuit of the same, as above described, whether a battery or a magneto is employed.

Furthermore, in order to guard against a mishap of both kinds; that is, anything 80 that might produce a transverse shock to the engine or a longitudinal shock also; I may use two of my attachments 8 with the same engine, by mounting one so that the bar will 85 be able to swing in a direction transverse to the crankshaft, as shown in Figures 2 and 3; and the other so that the bar can swing in a direction that is more or less parallel with the crankshaft. The two instruments 90 may both be arranged, for example, so as to ground the magneto 3, whichever one takes effect, by connecting the two instruments in parallel to each other; that is to say, simply by adding another instrument to the one 95 shown in Figure 1, and connecting its left hand terminal to the conductor 9 and its right hand terminal to the conductor 10. Then in case of a collision, whichever of the 100 two instruments allows its pendulum bar to swing in a direction parallel to the crank shaft will cause the short circuiting of the ignition system; and in case a shock occurring transversely of the engine, the other one will produce the required effect. With the 105 same effect I can also use the two attachments 8 in series with each other, and with the generator, such as a magneto or battery; using in each attachment one centrally located brush 27, connected to the binding post 25 at the left, and arranged to rest on the 110 bar 11; as already described; to break the ignition circuit instead of grounding it; but in any case of this sort, the two instruments 115 must likewise be arranged so that one will permit its pendulum bar to swing in a direction that extends longitudinally of the engine; and the other must be supported so that its pendulum bar is free to swing in a 120 direction across that axis. With two attachments on an aeroplane, the ignition system can be interrupted in case of an accident that is caused by practically any shock to the aeroplane substantially parallel to the plane of the wings, whether longitudinal or transverse, or even in diagonal directions; although the mode of operation will be best and surest of course when the shock is either directly transverse or directly along the 125 length of the engine.

In Figures 10 and 11 I show diagram-

matically a combination of parts which indicate how the instrument can be constructed so that a single pendulum bar can be utilized to interrupt the ignition system with 5 equal certainty in the case of a mishap; no matter whether the shock takes place lengthwise of the engine, or transversely of the same, or in any other direction so long as it is substantially parallel to the plane of the 10 wings or lifting planes 17. Instead of two contact elements 23 I utilize a conductor ring 53 with which cooperates a pendulum conducting bar 54 that is suspended at the middle of the ring and can swing when released 15 towards any point in the circumference of the ring. The lower end of this bar is rounded and it engages a head 55 having a shallow recess 56 which the end of the bar enters. The head 55 is carried on the upper end of a 20 stem 57 which is encircled by a helical spring 58 and normally tends to press the bar 57 toward the ring. So long as the bar 54 and stem 57 are in alinement, the bar 54 will be kept away from the ring, but in case of a 25 shock coming from any direction that is substantially parallel to the plane of the ring or even at some angle with this plane, the bar 54 will be shaken free from its engagement with the head 55 and impelled over towards the ring 53 until it is stopped by the latter. When this happens of course the spring 58 impels the head 55 upward, and this head will be surrounded by a suitable 30 insulating collar 59 which will slip behind the lower end of the bar and hold it against the ring 53 until the stem 57 is withdrawn to release the bar 54 and let it swing back to original position.

This stem 57 may be mounted to reciprocate in a bearing 60 against which one end of the spring 58 abuts, the other end abutting against the lower face of the collar 59; the upper face of this collar being rounded off or made approximately spherical. 40

At its upper end the bar 54 is likewise rounded, and abuts against a bearing member 61 having a rounded recess 62 which permits the end of the bar to move therein. Through the top of the bearing member 62 45 extends a short tubular section 63, and from the bar 54, through this section extends a flexible suspension element 64, such as a length of light chain or piece of wire, which passes through the section 64 and secures the upper end of the bar 54 in contact with the member 61. In other words, the suspension element 64 simply passes through a hole in the bar 54 up through the section 63 and may be hung at the top of the section 63, so as to draw the bar 54 against the lower end of the tubular element 63 and bearing member 61. This element thus suspends the bar and it will be connected to the ground wire 10 while the ring 53 will be joined to the wire 9.

When a shock takes place then the bar will swing over against the ring as shown in Figure 10, and the head 55 will serve the same purpose as the catches 34 above described. The bearing 60 will be slotted as 70 at 65 and through this slot will extend an arm 66 connected to the stem 57 to enable the operator to pull down the stem 57 when he desires to release the bar 54. Any suitable means may be employed to adjust the bearing 60 and regulate the force of the spring 58.

The part shown in Figures 10 and 11 may be mounted in a suitable casing which will be fixed to the aeroplane in such a manner as to respond to a shock to the engine, but must preferably be so arranged that the bar 54 will always be substantially vertical. After a shock produces contact between the bar 54 and ring 53 the operator has only to 80 pull down the stem 57 far enough to let the bar swing back and then let the stem go up again to cause the lower rounded end of the bar to enter the recess 56. Preferably the collar and the head 55 are flattened around this recess so as to provide a sufficient surface to engage the bar and steady it if, on the first attempt, the operator is not successful in bringing the end of this bar and the recess 56 together. In such a case only two 85 or three other attempts will be required before the bar will hang perfectly motionless on its suspension element 64, to enable the stem 57 to move the head 55 with the recess 56 directly against the lower rounded 90 end of the bar. Of course I may also provide a casing with buttons on the outside working against spring-plungers, like the plungers 38 above mentioned; and by pressing these plungers in with his fingers, the 105 operator can steady the bar 54, after depressing the stem 57 sufficiently, to bring about reengagement of this bar and the head 55 after the effects of an accident have been disposed of.

The combination shown in Figures 10 and 11 is illustrated as being adapted to short circuit the ignition system. It may also be utilized to break the main circuit of the ignition system directly, simply by connecting the wire 9 to the bearing 60 and insulating or dispensing with the ring 53. Current will then flow directly through the stem 57 and bar 54 and a shock will throw these two parts out of engagement and thus interrupt the flow of current.

Obviously the combination shown in Figures 10 and 11 will operate just as well if the bar 54 and stem 57 are held in horizontal position. If these two parts extend longitudinally of the engine they will respond to a transverse shock to interrupt the ignition system; and if they are supported in horizontal position, extending across the axis of the engine, they will respond to the shock 130

of a collision to interrupt the ignition system. In these two cases, however, the bar 54, instead of swinging, will always be apt to move downward and must be lifted again in order to bring it in alinement with the stem 57 and enable it to be re-engaged by same.

The construction shown in Figures 10 and 11 may have damping springs like those shown at 42, for example, four at right angles to each other, connected to the bar 54; and the collar 59 serves as retaining means when it is pushed toward the ring 53 to hold the bar and ring in contact. This type of attachment constitutes means comprising an element that can be moved either in a direction transverse of the longitudinal axis of the engine or in substantially the same direction as the axis to suspend the operation of the ignition system and stop the engine from rotating, without the position of the instrument being changed; once

it is supported so that the bar 54 and stem 57 are vertical; while, as pointed out above, in order to make the attachment 8 in Figure 25 1 operate in case of a longitudinal shock, the position of it must be changed so that the bar 11 can swing in the direction of the crankshaft 15.

Having described my invention, what I claim to be new, and desire to secure and protect by Letters Patent of the United States is as follows:—

Mechanism for stopping an internal combustion engine comprising a pivotally suspended bar, a contact element on each side of said bar, means for damping the oscillations of said bar, and means for adjusting said bar to neutral position between said elements.

In testimony whereof, I have signed my name to this specification this 4th day of December, 1917.

THEODORE DOUGLAS.
